UNITED STATES PATENT OFFICE

146,348

DESIGN FOR A PALETTE UNIT

Sophie Wallace Clippard, Columbia, S. C.

Application May 13, 1946, Serial No. 129,649

Term of patent 14 years

(Cl. D74—1)

To all whom it may concern:

Be it known that I, Sophie W. Clippard, a citizen of the United States, residing at Columbia, in the county of Richland and State of South Carolina, have invented a new, original, and ornamental Design for a Palette Unit, of which the following is a specification, reference being had to the accompanying drawing, forming part thereof.

Fig. 1 is a perspective view of a palette unit, showing my new design.

Fig. 2 is a top plan view of the disclosure in Fig. 1.

Fig. 3 is a side elevation.

I claim:

The ornamental design for a palette unit, as shown.

SOPHIE WALLACE CLIPPARD.
